UNITED STATES PATENT OFFICE.

ROBERT FREDERICK HALL, OF MOSELEY, ENGLAND.

MOTOR-DRIVEN VEHICLE.

SPECIFICATION forming part of Letters Patent No. 653,801, dated July 17, 1900.

Application filed September 14, 1899. Serial No. 730,482. (No model.)

To all whom it may concern:

Be it known that I, ROBERT FREDERICK HALL, engineer, a subject of the Queen of Great Britain, residing at Ferndale, Church 5 road, Moseley, near the city of Birmingham, England, have invented certain new and useful Improvements in Motor-Driven Vehicles, of which the following is a specification.

This invention has relation to motor-driven 10 road-vehicles propelled by oil and like explosion-engines, electricity, steam, or other motive power. Such vehicles commonly run upon four wheels, generally with the back pair being used as the drivers, while the front 15 pair are utilized for steering, and a common defect with all such vehicles is side slip and a tendency to turn around when the brake is applied suddenly or when at high speeds on greasy, inclined, or slippery surfaces.

20 The principal object of my invention is to overcome these defects and to equally distribute the driving wear and tear over the whole system, which is effected by making the whole of the wheels of the vehicle act 25 both as drivers and steers.

Further objects of my invention are to construct the vehicle wholly, or nearly so, of detachable parts, thereby facilitating manufacture and rendering everything accessible for 30 inspection, repair, and the like, to so construct the under carriage or framing of the vehicle that twisting of the same is obviated, and to improve and simplify the construction and arrangement of the speed and driving 35 gear of such vehicles.

Figure 1 of the accompanying drawings represents a side elevation of a road-vehicle propelled by an oil-motor and having four road-wheels of equal size, the whole of which 40 are so mounted and connected with the motor and the steering-gear as to act both for driving and steering in accordance with my invention. In this and the succeeding figures of the drawings the superstructure or body 45 of the vehicle, which may be of any suitable character or design, is not shown. Fig. 2 shows a plan of the said vehicle, and Fig. 3 is a view of the back end thereof. Fig. 4 represents a cross-section of the vehicle upon the 50 dotted line x , taken through the transversely swiveling joint which connects together the

front and back parts of the frame, which is so constructed for the purpose of obviating any liability to longitudinal twist in the structure. Fig. 5 represents, upon an enlarged scale 55 and partly in section and partly in elevation, the hub of one of the live-wheels, showing the construction of the joint by which it is swivelly connected to the driven axle in such a manner as to admit of the wheel being turned 60 for steering. Fig. 6 is a view showing a modified form of joint for connecting the driven axle to the live driving and steering wheel.

The same letters of reference indicate corresponding parts in Figs. 1 to 5 of the draw- 65 ings.

The vehicle illustrated in the said figures comprises a framing made up of two sections constructed in a rectangular form from an assemblage of tubular members and swivelly 70 connected together. The motor is mounted on the front frame and drives, by an arrangement of toothed gearing bands and pulleys, the axle of the rearmost pair of live road-wheels, while motion is communicated from 75 the rear axle to the other axle, which is mounted in bearings in the front frame, by chain-and-sprocket gearing. The steering is effected by mounting the whole of the wheels in vertically-pivoted forks coupled together, 80 so as to move collectively, by a system of connecting rods, levers, and flexible steel bands controlled and operated by a hand-wheel and rack and pinion.

Dealing first with the framing, a is the front 85 part or fore carriage, and b the rear part or rear carriage, the former consisting of pairs of parallel side tubes or members a' a'' , connected together at the front transversely by parallel members a^3 and vertically through 90 the medium of sleeve-like extensions d' of the split bearings d , wherethrough the front axle e of the vehicle passes, while at the back or inner end the sides are connected to vertical junctures or corner-pieces c^3 , the latter being secured in turn by means of four transverse tubes or stays a^5 , to a gapped end plate or bearing c^2 , constituting one of the members of the swiveling or yielding connection c , by 95 which the fore and rear parts of the carriage-framing are coupled together. The several members comprising this rectangular struc- 100

ture are preferably secured together by detachable mechanical joints, both for convenience in manufacture and to facilitate detachment when it is necessary to remove any of 5 the parts of the vehicle carried on the fore frame. The rear part of the framing is preferably longer than the fore part and consists of a similar rectangular assemblage of tubular members comprising two parallel side 10 pairs b' b'' , having parallel transverse stays b^3 at the rear end and braced vertically near the said rear end by the sleeve-like extensions f' of the split bearing f of the rear axle g , while the side tubes terminate inwardly in 15 junction-pieces c^4 , similar to and coinciding with the junctions c^3 at the inner corners of the fore carriage, and from which transverse stays b^5 proceed to the bearing-plate c^5 , opposed to and gapped to coincide with the 20 fore carriage end or bearing plate c^2 . The inner faces of these end plates c^2 c^5 come together and work upon one another when the two parts of the framing change their relative positions, and the connection between 25 the two sections is effected by a series of three bolts d^{10} d^{20} d^3 , the former two of which are passed, respectively, through coincident curved slots c^6 , formed in the opposed corner-junctions c^3 c^4 of the back and front frame 30 sections, which junctions come together and work upon one another in like manner as the middle bearings, while the third bolt d^3 takes through a coincident pair of curved slots c^7 , made in the upper parts of the said middle 35 bearings or opposed elements c^2 c^5 of the swiveling connection c . Further, in order to admit of the said connection having a certain amount of longitudinal play or elasticity, pairs of rubber washers d^4 are strung upon 40 the bolts and arranged to come upon the opposite sides of the connected parts, while fiber or vulcanite rubbing-pieces may be disposed between the opposed faces of the two halves of the joint to minimize friction. 45 The motor is suitably mounted upon the fore carriage and consists in the arrangement shown of a pair of independent engines g' of any suitable type, collectively driving a drum g^2 ; which acts as a fly-wheel, this system being preferred from the fact that in the event 50 of a breakdown of either engine it may be uncoupled from the drum and the other engine used alone to propel the vehicle. The drum g^2 carries or is fashioned into a pair of 55 pulleys g^3 g^4 , from which a pair of crossed high-speed driving-bands g^5 g^6 proceed rearwardly to the speed-gearing, which is designed to give only two speeds and is arranged as follows:

60 Mounted upon a dead-spindle h , supported by a pair of brackets h' , detachably secured to the transverse stay members b^3 of the rear carriage, are two pairs of fast and loose pulleys h^3 h^2 and h^4 h^5 , the former pair being 65 driven by the belt g^5 from the engine-drum g^2 , while the latter pair are driven by the other band g^6 from the second drum. The

fast pulley h^2 is keyed to a sleeve or bush surrounding and working upon the spindle h , while the other pulley h^3 revolves idly either 70 upon the spindle or the bush, an end of which latter extends into a gear-case f^2 , longitudinally divided into two detachable halves and carried by the axle and counter-shaft. Inside the gear-case the sleeve of the live-pulley is 75 fitted with a small pinion (not shown in the drawings) gearing for high speed with a large toothed wheel made fast to a driven sleeve f^4 , through which the rear axle g passes, the said sleeve and axle being coupled together 80 for driving purposes by a balance-gear of any ordinary construction contained within the casing f^6 for the purpose of admitting of the road-wheels, with the axle and the driven shaft, rotating at differential rates when the 85 vehicle is turning a corner. The other fast pulley h^4 , driven by the second belt g^6 , is connected with a larger slow-speed pinion, engaging with a toothed wheel inclosed within a second gear-case f^3 and made fast to the driven pinion. 90 It will thus be seen that when the band g^5 is thrown onto the pulley h^2 the vehicle is driven at a high speed, the other band g^6 meantime running idly on the loose pulley h^5 ; but when the belts are shifted by suitable means so as 95 to transfer the belt g^5 to the loose pulley h^3 and the belt g^6 to the fast pulley h^4 then the high-speed gear is thrown out of action, and driving at the lower rate of speed is effected through the pinion on the sleeve of the pulley h^4 . On the other hand, when both the 100 bands are thrown onto the loose pulleys then the motor is disconnected from the driving-gear and axle and runs idle while the carriage stands stationary.

For the purpose of driving the front axle e at the same speed as the rear axle g the driven sleeve f^4 is provided in the longitudinal center of the vehicle with a toothed wheel f^7 , gearing by means of a drive-chain i with another toothed wheel d^7 of the same size, secured to a driven sleeve d^4 , through which the front axle e passes, with driving connection between the said sleeve and axle being established by a balance-gear inclosed within the 110 casing p^6 and so arranged that normally both the axle and its sleeve rotate together at the same speed.

Each of the road-wheels j' j^2 and k' k^2 is mounted and runs between the branches of 115 a steering-fork m , of which the crown m' has a short vertical post or pivot m^2 , working within a socket m^3 , carried by an arm or end m^4 of a transverse member b^8 of the framing, the said post being retained in the socket by 120 nuts m^5 taking upon the upper screwed end of the same, while ball-bearings are interposed between the contacting surfaces of the working parts to minimize friction. Each fork consists of two opposite pairs of blades, 125 m^6 and m^7 , each detachably connected at their upper ends to the crown m' by means of bolts m^8 . At their lower ends the inner pair of blades m^6 come together and terminate in a

common fitting m^9 , which is jointed at m^{10} to a ring m^{11} , constituting a suspended bearing for the wheel-hub n , while the lower and converging ends of the outer blades m^7 terminate in a similar fitting m^{13} , which is detachably jointed at m^{14} to a second suspended hub-bearing n^2 .

The hub n of each road-wheel comprises a body n' , of which the inner and larger end n^3 works within the fixed suspended ring-bearing m^{11} , with antifriction-rollers m^{12} interposed between them, while at the outer end the hub-body is made fast to an internal fitting n^4 , whose shank n^5 is connected by a universal joint o to the driven axle, so that the two road-wheels of both the driven front and back axles are coupled to the said axles by joints which both transmit the rotary motion for driving and permit of the said wheels being turned, with their forks, about a vertical center for steering, and preferably the said swivel-joint is arranged to come exactly in the center of the wheel, so that in the event of the wheel in running striking against any obstruction lying in its path it readily mounts the same without any leverage likely to distort the wheel or set up shock being created, such as would be apt to occur if the center of the joint was out of the wheel-center. The forward extension n^6 of the fitting n^4 is provided with a pair of bearing-cones n^7 n^8 , the inner one of which comes up to an abutment n^9 and is prevented from rotating by pegs n^{10} , while its shank n^{11} is screwed, and the outer cone n^8 takes and is adjustable thereon for the purpose of taking up any slack which may occur in the outer hub-bearings, comprising two sets of antifriction-balls n^{12} n^{13} , located, respectively, in races formed by the half-races of the live or rotating cones n^7 and n^8 and opposed half-races n^{14} n^{15} , in the stationary or dead element formed by the fork-suspended part n^2 , which is screwed to receive the dust-cap n^{16} . n^{17} are the nuts, and n^{18} the washer, by which the cones are retained in place upon the extension n^6 of the hub-body. These bearings are entirely self-contained and may be removed bodily from the hub by disconnecting the outer fork-blades, removing the dust-cap, and unscrewing the lock-nuts.

To prevent dust and the like gaining access to the inside of the hub from the inner end and yet without interfering with the swiveling movement of the wheel relative to the axle, a sleeve or sheath p , of flexible material, is provided, the inner part of which is secured to the body of the hub by means of a ring p' , while the outer end is made fast in like manner by a ring p^2 to the axle.

For the purpose of effecting the steering of the vehicle through the medium of the four live or driven road-wheels I employ a system of levers and connections arranged in the following manner: Mounted upon suitable bearings q' , preferably detachably fitted to the members of one side of the rear frame, is a

spindle q , provided at one end with a steering hand-wheel q^2 , arranged to come within convenient reach of the driver of the vehicle and having a toothed wheel q^3 , which gears with a rack r' cut in the edge of a sliding rod r , working within a pair of guides r^2 , which may also be removably fitted to the framing side, both for convenience in manufacture and to facilitate repair. To the rearmost end of the slide is jointed a connecting-rod r^3 , terminating in and jointed to the one end of a lever s , made fast to a vertical steering-pillar s' , carried by a pair of bearings s^2 , detachably connected by means of clips s^3 to the transverse stay members b^3 of the rear framing, while the extreme upper end of the said pillar works in a third bearing s^4 , carried by the rear end of a stay b^6 , secured by a clip b^7 or other mechanical or detachable joint to the transverse framing member b^8 , before referred to, and which is arranged to come between and brace together the bearing-sockets m^3 of the wheel-forks and is supported in an elevated position above and parallel with the rear axle by vertical members b^9 , extending from the framing b . At or near its upper end the said steering-pillar is provided with a double-armed lever or triangular frame t , the ends of the two angularly-disposed branches t^2 of which respectively have jointed to them the inward terminations of a pair of connecting-rods t^3 and t^4 , the former proceeding and being jointed to an arm t^5 , projecting rearwardly from the crown of the fork of the left-hand rear road-wheel, while the latter proceeds and is jointed in like manner to a similar arm t^6 , carried by the fork-crown of the right-hand rear wheel.

To insure the front driven wheels being moved in unison with the back pair for steering, I secure, preferably, to the lower end of the steering-pillar s' a cross-piece or straight double-armed lever s^5 , and at the front of the fore part a of the vehicle-framing I arrange a second steering-pillar u' , supported in bearings u^2 u^4 , the latter pair being detachably connected to the transverse framing members a^3 and the former by a supplementary stay a^6 , attached by a clip a^7 to a transverse frame-tube a^8 , supported by uprights a^9 and bracing together the bearing-sockets of the front wheel-forks. The lower end of this pillar u' is provided with a double-armed lever u^5 , the counterpart of the one s^5 on the rear pillar, and the two levers are connected together by means of a pair of crossed flexible steel bands u^1 u^2 , of which the one is jointed at rear end to the left-hand branch of the lever s^5 and at the front end to the right-hand branch of the lever u^5 , while the ends of the other band are jointed to the other branches of the two levers. Near the summit of the pillar u' is an angle-lever w , the counterpart of the lever t at the back, and whose branches w^1 w^2 are respectively coupled to forward arms w^5 w^6 , extending from the fork-crowns of the two front road-wheels by connecting-rods

$w^3 w^4$. By the employment of such a double system of levers and connecting-rods with flexible metal bandings coupling together the front and back parts of the system, in conjunction with swiveling joints between the driven axles and their road-wheels, it follows that when the driver rotates the steering-wheel motion is communicated in common to the whole of the levers, and the road-wheels, through their forks, are taken into positions more or less at an angle relative to their axles, according to the radius of the curve to be turned, while by the interposition of the angular levers t and w I insure that the wheels which come innermost on a curve and have to describe a smaller circle shall assume a more acute angle relative to the axles than the outermost wheels. (See the positions indicated by the dotted lines in the plan view, Fig. 2.)

Adverting again to the construction of the framing and to the manner in which the various parts are assembled together and secured by detachable mechanical joints, I may say that the sections of the split bearings d and f within which the live driving-sleeves run may be connected together by pins or bolts x and clips x' at the tops and bottoms of the sleeves or extensions $d' f'$, which clips also serve to detachably secure the upright members $a^9 b^9$, supporting the transverse fork socket-braces $a^8 b^8$, and also (through the medium of the sockets x^2) the transverse end members a^3 and b^3 , with their corner-lugs $a^{10} b^{10}$ and short tubes $a^{11} b^{11}$, to the front and rear body-sections of the main framing. By such a construction it is rendered possible to remove either of the steering-pillars (after the flexible steel bands have been disconnected) and the levers carried by them by detaching the upper lever t or w from its connecting-rods and then unfastening the clips s^3 or u^3 and b^7 or a^7 , by which the bearings $s^2 s^4$ or $u^2 u^4$ are secured to the transverse frame-tubes $b^3 b^8$ or $a^3 a^8$, respectively. The outer bearings of the wheel-hubs are also removable (as previously described) after the outer fork-blades have been disconnected from their crowns, while after the steering-pillars and their levers have been removed and the drive-chain i unfastened either of the driven axles, with its sleeve and the parts of the driving-gear carried thereon, may be removed bodily, with the road-wheels and the said frame members, from the main framing by withdrawing the bolts x and detaching the clip connections x' . Further, when the driving-belts $g^5 g^6$, drive-chain i , and steering-bands $v' v^2$ have been removed the front of the framing carrying the motor and its cognate parts may be readily separated from the back part carrying the speed-gearing by removing the bolts $d^{10} d^{20} d^3$ of the flexible or yielding connection e . The withdrawal of the dead-spindle h permits of the detachment of the fast and loose pulleys of the speed-gear, while the brackets h' and the sectional gear-case may also be

taken away and replaced with ease should circumstances necessitate it.

Instead of employing a universal ball-joint for connecting the axles to the hubs of the driven and steering wheels, such as shown in Fig. 5, I may use a form of hook-joints, such as shown in Fig. 6, or any other suitable form of joint or swiveling connection may be used which will transmit the movement of the driven axle to the road-wheels and at the same time permit of the said wheels being turned to any angle that may be required for steering purposes.

Having fully described my invention, what I desire to claim and secure by Letters Patent is—

1. A running gear for motor-driven vehicles, comprising two separate rectangular frames centrally swiveled together at their adjacent ends so as to turn about a horizontal axis, and endwise-yielding connections connecting the adjacent ends of said frames together, whereby said frames are free to turn independently of one another about a horizontal axis and also move longitudinally away from and toward each other, substantially as described.

2. In a motor-driven vehicle, the combination with two separate frames flexibly connected and centrally swiveled together at their adjacent ends, a front and rear axle, respectively carried by said frames, and ground-wheels carried by said axles, of a motor carried by the forward frame, differential gearing connecting said motor with the rear axle, and gearing connecting the rear axle to the front axle to cause said axles to rotate in unison, and steering mechanism arranged to turn all four of the driving-wheels about their vertical axes simultaneously, substantially as described.

3. In a motor-propelled vehicle, the combination with two separate frames flexibly connected and centrally swiveled together at their adjacent ends, of a front and rear axle respectively carried by said frames, ground-wheels carried by said axles, a motor carried by the forward frame, differential gearing connecting said motor with the rear axle, gearing connecting the rear axle to the front axle to cause the said axles to rotate in unison, and steering mechanism arranged to simultaneously turn the front and rear wheels laterally at opposite angles, said steering mechanism being constructed and arranged to turn the front and rear wheels on the side toward which the vehicle is turned at a more acute angle than the front and rear wheels on the other side, substantially as described and for the purpose specified.

4. In motor-driven vehicles in which the framing, or the underframing is made in two separate or detachable and transversely or cross divided parts, coupling or securing together the said parts by a swiveling and yielding joint, consisting of a pair of end bearing-plates or their equivalent respectively fitted

to the opposed ends of the two parts of the frame and having curved coincident gaps through which bolts are passed, with or without rubber or elastic washers strung upon 5 their opposite ends, substantially as and for the purpose herein described.

5. In motor-driven vehicles in which wheels are utilized for both driving and steering, the construction of the wheel-hubs, with inner 10 and outer bearings suspended from the sides of the steering-forks and with centrally-lo-

cated universal or swiveling joint connections between them and the driven or "live" axles, substantially as herein described and set forth.

In testimony whereof I have hereunto set my hand in presence of two subscribing witnesses.

ROBERT FREDERICK HALL.
